FIG. 1.

FIG. 2.

INVENTOR

Morris Green

UNITED STATES PATENT OFFICE

108,833

DESIGN FOR A GILET

Morris Green, New York, N. Y.

Application February 4, 1938, Serial No. 74,881

Term of patent 3½ years

To all whom it may concern:

Be it known that I, Morris Green, a citizen of the United States of America, residing in New York city, in the Borough of Manhattan, county and State of New York, have invented a new, original, and ornamental Design for a Gilet, of which the following is a specification, reference being had to the accompanying drawing, forming part thereof, wherein,

I claim:

The ornamental design for a gilet, substantially as shown.

MORRIS GREEN.
